UNITED STATES PATENT OFFICE.

JOHN F. McAFFEE, OF PLEASANT HILL, MISSOURI.

YARN-HANKING MACHINE.

SPECIFICATION forming part of Letters Patent No. 271,889, dated February 6, 1883.

Application filed May 16, 1882. (No model.)

To all whom it may concern:

Be it known that I, JOHN F. McAFFEE, of Pleasant Hill, in the county of Cass and State of Missouri, have invented a new and Improved 5 Yarn-Hanking Machine, of which the following is a full, clear, and exact description.

My improvements relate to machines for forming woolen and cotton yarns into hanks, and have the object to facilitate the work and 10 give to the hanks a better shape and appearance.

The invention consists in the combination of the mechanism hereinafter described and claimed, and in which the hook that receives 15 the hank of yarn is fitted for throwing the mechanism in and out of gear.

Reference is to be had to the accompanying drawings, forming part of this specification, in which similar letters of reference indicate corresponding parts in both the figures.

Figure 1 is a perspective view of my improved hanking-machine. Fig. 2 is a vertical section on line α α of Fig. 1.

A is a suitable frame, carrying the mechanism, which frame is to be fastened to a post or a table in any convenient position for connection with power.

a is a shaft fitted for endwise movement in its bearings, and provided at one end with a 25 clutch-face, b, and carrying a gear-wheel, e.

e is a hollow shaft upon the shaft a, carrying a fast pulley, d, and provided at its outer end with a clutch-face, f, next to the clutch-face b. This shaft e is to be driven continuously by a band from the pulley d to a pulley 35 on the line-shaft.

g is a shaft fitted upon the frame parallel to the shaft a, provided with a pinion, h, for engagement with the gear-wheel e, and fitted at 40 its outer end with the hook i for receiving the hank of yarn. The other end of the shaft g connects to the lever k, which is hung at the side of the frame. This lever also engages or passes between collars upon the clutch-shaft 45 a, and to the opposite end of this lever k is connected a spring, l, which tends to draw the lever in the direction for disengaging the clutch b f, and for releasing the pinion h from the gear-wheel e.

50 In operation, the hank of yarn is placed upon the hook i, and then by pulling the hank gently it moves the shaft g endwise, thus engaging

the pinion h with the gear-wheel, and moving the shaft a backward, so that the clutch-faces b f engage. This causes the hook to revolve 55 six, eight, or more times, as may be required, and gives the required twist to the hank of yarn. In order to stop the hook in an upright position convenient for taking off and folding the hank, the gear-wheel e is provided with a 60 lug or projection, m, in position for entering into a notched piece, n, that is fastened on the frame, so that when the pull on the hank is released and the shaft a drawn back by the spring this projection m will enter the notch 65 of the piece n and arrest the movement of the gear-wheel at the required place by leaving the hook upright.

The small amount of tension required upon the hank in order to throw the machine into 70 gear acts to straighten the yarn and to give to the hanks a better shape.

The machine is durable in construction, and there is nothing about it liable to get out of order. The work is also done rapidly, with a 75 saving in labor.

The machine is intended for hanking all kinds of yarns and twines, wool, cotton, flax, hemp, or jute.

Having thus fully described my invention, 80 what I claim as new, and desire to secure by Letters Patent, is—

1. In yarn-hanking machines, the combination of the shaft a, provided with clutch-face b, the hollow shaft e, provided with clutch-face f, adapted to engage with the clutch-face b, the shaft g, provided with the hook i, lever k, connected to the shaft g and to the shaft a, and the gear-wheels e h, all substantially as described, combined for operation as set forth. 90

2. In yarn-hanking machines, the combination, with the shaft a, of the shaft g, provided with hook i, and fitted for endwise movement in the bearings, the lever k, connected to the shafts g and a, the driving-shaft e, and the clutch-faces b f, fitted for engagement by endwise movement of the shaft a, substantially as described, combined for operation as set forth. 95

JOHN FRANKLIN McAFFEE.
